HAIR DRYING APPARATUS

Victor C. Norquist, Kansas City, Mo., assignor to
 Butler Manufacturing Company, Kansas City,
 Mo., a corporation of Missouri

Application December 1, 1932, Serial No. 645,249

4 Claims. (Cl. 34—26)

My invention relates to a hair drying apparatus and more particularly to a hair drying system in which a central gas-fired hot air generator supplies heated air for a plurality of individual hair drying helmets.

In beauty parlors at present, when it is desired to dry the hair, individual driers are used. These individual hair driers are usually electrically heated and are expensive and inefficient in operation. When the devices are turned on, a considerable time interval must elapse before the temperature required to heat the air is reached and this period of heating not only requires time but also consumes electricity. The individual driers are not particularly well insulated so, if many of them are in operation, the space in which they are being used becomes heated. This is particularly objectionable as will readily be understood, on a warm day.

One object of my invention is to provide a hair drying apparatus in which a plurality of hair drying helmets may be used simultaneously with a central source of hot air.

Another object of my invention is to provide an economical and efficient means of generating and supplying hot air to a plurality of hair drying helmets.

A further object of my invention is to provide a hot air generator for my hair drying apparatus having a novel method of preventing heat radiation into the space occupied by my apparatus.

Another object of my invention is to provide a hair drier unit provided with thermostatic means for keeping the temperature of the air being used for drying purposes uniform.

Another object of my invention is to provide a method for keeping the outlet temperature of the drying air at each of the outlets substantially uniform.

Other objects of my invention will appear from the following description.

In the accompanying drawings which form part of the instant specification and which are to be read in conjunction therewith and in which like reference numerals are used to indicate like parts in the various views:

Figure 1 shows a side elevation of my hair drying apparatus with one of my hair drying helmets, the conduit being broken away in part.

Figure 2 is a sectional elevation of the hot air generator of my hair drying apparatus taken along the line 2—2 of Figure 1.

Figure 3 is a sectional plan view through my

hot air generator along the line 3—3 of Figure 2.

Figure 4 is a sectional view taken along the line 4—4 of Figure 2.

Figure 5 is a sectional view taken along the line 5—5 of Figure 2.

Figure 6 is a sectional view taken along the line 6—6 of Figure 2.

Figure 7 is a sectional view showing the method of supporting the end of the hot air conduit.

Figure 8 is a sectional view taken along the line 8—8 of Figure 1.

Figure 9 is a sectional view taken along the line 9—9 of Figure 3.

Figure 10 is a sectional view taken along the line 10—10 of Figure 1.

Figure 11 is a sectional view of my thermostatic control means.

Figure 12 is a sectional view taken along the line 12—12 of Figure 11.

Figure 13 is a sectional view taken along the line 13—13 of Figure 11.

Figure 14 is a sectional view taken along the line 14—14 of Figure 11.

Figure 15 is a fragmentary sectional view showing the alternative method of mounting the hair drying helmet supporting duct to the hot air supply conduit to permit universal adjustment of the helmet.

In general, my invention contemplates the provision of a central, gas-fired hot air generator to which a conduit is connected. A plurality of ducts which may be as many as desired, are connected to the supply conduit and support helmets. In practice, I have used as many as ten helmets on a single conduit with complete success. The generator is supplied with a gas burner which is lighted automatically by a thermostat disposed in the hot air outlet of my furnace. This thermostat also controls the burner to keep the temperature of the outlet air substantially uniform. A blower takes suction through a screen at the upper part of my generator which is provided with a passage-way between the heating unit per se and the casing so that a blanket of cold air will prevent radiation of heat into the space occupied by my generator. The air is forced by a blower upwardly through a baffled annular jacket which is provided with heat exchange fins. The hot air generated by my apparatus is fed to an inner conduit suitably supported and extending across the room occupied by my apparatus. Suitably supported from this conduit are a plurality of branch ducts carrying hair drying helmets of

any suitable design. I provide means for automatically conducting air to the branch ducts when the helmet is moved to the position occupied during its use.

5 More particularly referring now to the drawings, a hot air generator 1 is connected to a supply conduit 2. A plurality of branch ducts 3 support a plurality of respective hair drying helmets 4. The duct 2 may be supported in any 10 suitable manner. I have shown a stanchion 5 supporting the conduit 2 by means of a novel end member 6 as will be hereinafter more fully described.

The hot air generator 1 is provided with an external casing 10 in which is supported an annular jacket member 11. The jacket member 11 comprises a pair of spaced walls held in spaced position by a plurality of circular perforated baffles 12. The internal wall 13 of the jacket member 11 is provided with a number of fins 14 which are formed by bending the internal jacket wall 13 upon itself. These fins can be readily seen by reference to Figure 3. The external casing 10 is provided with a perforated section 15 near its upper end. A central passageway 16 is formed in part by the internal jacket member 13 and a cylindrical member 17. The lower portion of the casing 10 houses a motor 20 which is supported in any suitable manner such as on resilient pad 21 to reduce the noise of its operation. The motor 20 drives a blower fan 22 of any suitable type. I have found a sirocco fan the most suitable. The fan throws air through outlet 23. A flexible coupling 24 connects fan outlet 23 with a duct 25. By preventing metal to metal contact, elimination of noise is effected. Around the cylindrical member 17 and within the lower portion of the jacket space I provide a circular gas burner 26. A pair of ducts 27 take air by natural draft from the lower portion of the casing through suitable inlet holes 28 and supply it to support the combustion of the gas burned in my gas burner 26. A gas supply pipe 29 is controlled by a valve 30 which is operated by a solenoid 31. The solenoid 31 is controlled by thermostat 32 which is disposed in the air outlet from my hair drying generator on the way to the air supply conduit. Within the central jacket space 16 and running axially of the heat exchanger portion 50 of my hot air generator, I position a pipe 33. The lower end of this pipe extends to the region of the air supply 25. The upper end of this pipe 33 terminates in a conduit 34, the purpose of which will be hereinafter more fully described. In the 55 circuit which controls the solenoid 31 I provide a transformer 35 adapted to increase the voltage sufficiently to jump a spark across contacts 36 which are positioned above the burner holes. This spark serves to unite the gas-air mixture 60 coming from the burner holes of my burner 26.

The operation of the hot air generator will now be described. When it is desired to operate my generator a switch 37 is operated. The operation of this switch starts the motor 21, which in 65 turn drives the fan 22. Air is taken through holes 15 of the casing 10. It will be observed that these holes are in the upper part of the room near the ceiling in the region in which the hottest air present in the room will collect. This 70 air is drawn downwardly through the jacket formed by casing 10 and heat exchanger jacket 11, as will be readily appreciated by reference to Figure 2. The air passing through the annular jacket serves to form an effective blanket 75 against the radiation of heat into the space oc-

cupied by my generator and, at the same time, will heat the air by contacting with the external wall of the heating jacket 11. This air thus pre-heated is picked up by blower 22 and forced upwardly through connection 25 into the cylindrical member 16 and passes upwardly through the internal heating conduit in contact with heat exchange fins 14. When the switch 37 is operated, the air of course will be cold. The thermostat will thus permit the proper electrical connections to be made to actuate solenoid 31 which will open the gas supply valve 30. At the same time, transformer 35 will be actuated and a spark will be present between contacts 36. This will ignite the gas and light the burner 26. The products of combustion will pass upwardly through the heating jacket 11. Its passage will be delayed by annular baffles 12 which will in turn become heated and serve to heat the jacket walls by conduction. At the same time, the hot products of combustion will heat the walls per se by convection. The hot products of combustion leave the top of the heating jacket 11 through any suitable flue pipe 38. Air is continuously supplied to the burner through ducts 27 and gas is continuously supplied through gas supply pipe 29. After the air reaches the desired temperature, the thermostat will operate and cylinder 31 will be de-energized. This will permit the valve 30 to close. At the same time, the spark jump between contacts 36 will cease. The blower fan will continue to run. At such time as the thermostat drops below the set point, the thermostat will again take charge and the burner will be again lighted.

The thermostat 32 comprises a casing 40 which may be mounted in any suitable manner. One side of the casing 40 is provided with a flange plate 41 to which a supporting arm 42 is secured by means of a rivet 43 or in any other suitable manner. This plate may be rotated around the casing 40. Its position is determined by pointer 44 which is attached to the casing. The supporting member 42 carries the thermostatic element which consists of a helical spring 45, the internal end of which carries a glass tube 46 in which a quantity of mercury is positioned. One end of tube 46 is arranged for the introduction of conductors 47 and 48. These flexible conductors terminate in switch members 49 and 50 which are suitably supported between insulating disks 51. The switch members contact with conductor rods 52 and 53 to which the conductors 54 and 55 are attached. The circuit is open between conductors 47 and 48. Normally, the glass tube 46 is tilted to such an angle that the mercury 55 will complete the circuit between the ends of the conductors 47 and 48 as is shown in Figure 14. Thus, when the switch 37 is operated, the circuit is completed to permit the solenoid 31 to turn on the gas supply.

It is of course understood that the motor 20 is controlled independently of the thermostat. When the air becomes heated beyond a predetermined point, the helical spring 45 will expand. In expanding it will tilt the glass tube through an angle as shown in Figure 13. Mercury will then flow away from the region of the conductor inlet and permit the circuit to break. The angle through which the glass tube must move before this can take place is determined by the initial position of the glass tube when cold. It will be observed that by rotating cover plate 41 that the support 42 will rotate helical spring 45. In this manner I may adjust the degree of heat which I desire. When cover plate 41 is rotated, the switch 75

members 49 and 50 will make sliding contact over the ends of conductor rods 52 and 53. If I rotate the cover plate through an angle large enough to permit the switch members 49 and 50 to leave contact members 52 and 53, the device is definitely turned off so that the gas will not be turned on regardless of the position of the glass tube 46.

It will be observed that hot air capable of drying hair is generated by the device just described. 10 The hot air leaves the top of my generator by means of elbow 61. The conduit may be of any suitable cross section. It is composed of a number of sections 62 which are joined together by 15 means of a coupling member 63 as can be readily seen by reference to Figure 10. The end of the conduit terminates in a cap casting 64 which is provided with a socket 65 into which a stanchion 5 is fitted. I am enabled to adjust the level of 20 the conduit by means of set screw 66. Another set screw 67 is provided in my base member 68 to admit of further adjustment. This assembly can be seen by reference to Figure 7. The bottom of 25 the conduit 2 is provided with a plurality of openings around which is positioned a collar 70 secured to the conduit in any suitable manner such as by rivets 71. To the ring 70 I secure, in any suitable manner, a branched duct 72 in which is telescoped a duct 73 which terminates in a hair 30 drying helmet 4. A flexible member 74 may be of piano wire or any suitable flexible material. One end of the flexible member 74 is secured to the telescoping duct 73 by any suitable suspension 35 75. The other end of the flexible member 74 is secured to a spring roller 76 which is housed in a suitable housing 77, supported by supporting member 77a. The tension of the spring is such that the weight of the telescoping duct 73 and the helmet 4 will be substantially counter balanced. At the end of branch duct 72, I provide 40 a cap member 78 in which is positioned a felt washer 79, the internal periphery of which engages the telescoping duct 73. By adjusting the cap member 78, the friction between the telescoping duct 73 and the felt washer 79 may be adjusted. I provide another washer 80 within the 45 branch duct 72, and attached to telescoping duct 73, as can be seen by reference to Figures 8 and 9.

Normally, the end 81 of the telescoping duct 73 50 bears against a pad 82 of compressible material such as felt, as can be seen by reference to Figure 8. It will be observed that the peripheral edge 81 of the telescoping duct 73, when engaging pad 82, will form a tight joint so that no air 55 in conduit 2 will find its way into telescoping duct 73. In other words, the peripheral edge 81 and the pad 82 form a valve. When the telescoping duct 73 is pulled downwardly as shown in Figure 60 9, the effect is to put the telescoping duct 73 in communication with the conduit 2 through branch duct 72. Thus, I provide automatic means for placing the telescoping duct in communication with the hot air supply, when the telescoping duct is moved to a position which it will occupy during its use. Normally, I provide helmets 65 4 at the ends of the various telescoping ducts 73. These helmets form no part of the instant invention and are well known in the art. I may also provide at the end of branch duct 73 a flexible member 84 which terminates in a nozzle 85. This particular fitting is to be used in treating 70 long hair. It frequently happens that certain parts of the hair are not dried by the helmet if the hair is long. By using the nozzle 85, which 75 may be directed to those parts of the hair which

are slightly damp, a final drying may be effected by an operator.

In Figure 15, I show a modification in which the branch conduit 72 is supported by means of a universal joint which comprises a ball member 5 90 and socket members 91 and 92. This will permit the universal positioning of the hair drying helmet.

It frequently happens that a temperature drop will take place of one or two degrees between the helmet nearest my generator and that most remote. In order to insure that all the helmets will be at a uniform temperature, I position a duct 34 which is described above, in the bottom of the main air conduit 2. This duct 34 can be seen in 10 position in Figure 1. It stops just short of the first helmet. Cold air will pass through pipe 33 and issue from the end of duct 34. This cold air will lie along the bottom of the conduit and flow into the first helmet. A portion of it will become 15 diffused with the air and flow into the second helmet. In this way, I am enabled to reduce the temperature of the first and second helmets somewhat so that there will be a uniform temperature at all helmets in use. I also provide a 20 sloping baffle plate 93 within the conduit 2. This baffle plate is so arranged that the volume within the duct decreases progressively toward the helmet most remote from the generator. I am enabled by this arrangement to insure a uniform 25 supply of air to all of the helmets. 30

It will be seen that I have accomplished the objects of my invention. I am enabled to supply hot air to a plurality of hair drying helmets in an economical and efficient manner. I have 35 found that the method of heating air by a gas burner in my device will consume about one fifth as much gas as known types.

The users are relieved of annoying mechanical noises. The thermostatic control operates automatically and delivers the air flow at the exact degree of temperature to which the thermostat is set. The air duct being positioned at a point remote from the immediate vicinity of the users, discomfort from radiant heat is prevented. A high 40 degree of efficiency in heat exchange is effected by my construction and all danger of escaping gas is precluded by means of my ignition arrangement. The jacket of cold air going to the generator prevents the escape of heat into the space 45 being occupied, thus preventing its overheating. 50

It will be understood that certain features and sub-combinations are of utility and may be employed without reference to other features and sub-combinations. This is contemplated by and 55 is within the scope of my claims. It is further obvious that various changes may be made in details within the scope of my claims without departing from the spirit of my invention. It is, therefore, to be understood that my invention is 60 not to be limited to the specific details shown and described.

Having thus described my invention, what I claim is:

1. A hair drying assembly comprising an air 65 source, a duct communicating with said air source, an air distributing means, a tube telescoped within said duct and communicating with the air distributing means, and an occluding member against which said tube is adapted to seat, the 70 construction being such that the seating of the tube stops the air supply thereto and the lifting of the tube from the occluding member permits the flow of air from the air source to the distributing member. 75

2. A hair drying assembly comprising in combination an air conduit, a duct communicating therewith, a tube telescoped within said duct, air distributing means carried by said tube, a pad mounted within said conduit against which one end of said tube is adapted to seat, means for substantially counterbalancing said tube, the construction being such that air may flow through said tube when it is moved from the pad.
- 10 3. A hair drying assembly comprising in combination a hot air generator, a manifold communicating with said generator, a branch duct communicating with said manifold, a ball and socket mounting means for said branch duct, a tube mounted in said branch duct and telescopically movable therein, an air distributing helmet carried by said tube, means for substantially counterbalancing said tube and helmet, and means for continuously creating frictional resistance to telescopic movement of said tube in said branch duct.
